UNITED STATES PATENT OFFICE.

CHARLES EUGENE MILLER, OF CHICAGO, ILLINOIS, ASSIGNOR, BY MESNE ASSIGNMENTS, TO AMERICAN ARCH COMPANY, OF NEW YORK, N. Y., A CORPORATION OF DELAWARE.

FIRE-ARCH.

1,138,043.

Specification of Letters Patent.

Patented May 4, 1915.

Application filed January 15, 1912. Serial No. 671,354.

To all whom it may concern:

Be it known that I, CHARLES E. MILLER, a citizen of the United States, and a resident of Chicago, Cook county, Illinois, have 5 invented certain new and useful Improvements in Fire-Arches, of which the following is a specification.

My invention relates generally to improvements in boiler furnaces, and it relates more particularly to improvements in 10 baffle walls or fire arches of the type adapted particularly for locomotive boiler furnaces that are equipped with arch supporting tubes.

15 The general object of my invention is to improve the form, arrangement, and construction of such arches to enable the same to be built at low cost, to be installed easily, and to be maintained in working order at 20 maximum efficiency, with but little attention.

Another object of my invention is to provide a sectional arch for locomotive fire boxes having a group of arch tubes, which 25 shall be easily adjustable to irregularities in the spacing or arrangement of the arch supporting tubes and side sheets, in order that a limited number of brick sizes will accommodate or be suited to all sizes of locomotive fire boxes; and a further object is 30 to provide a sectional brick fire arch supported upon arch tubes in a locomotive fire box and arranged and positioned so that cracking or breaking of individual arch 35 bricks will not disturb the other bricks of the arch, and will not seriously impair the effective operation of the arch.

40 My invention consists generally in a locomotive boiler fire box comprising a group of arch tubes longitudinally arranged therein, a plurality of bricks resting upon the tubes and abutting each other, said bricks being adapted for limited transverse movement in the fire box, and inclined key bricks 45 resting upon the outermost of the tube supported bricks and wedgingly abutting the side sheets.

50 My invention consists further in an arch for locomotive fire boxes equipped with a group of arch supporting tubes of less width than the fire box, a plurality of bricks resting upon said arch tubes and abutting each other, said bricks being substantially co-extensive with the group of arch tubes, por-

tions of said bricks projecting between the 55 tubes in manner to permit slight transverse movement of the bricks, and key bricks resting upon the outermost tube supported bricks and wedgingly abutting the side sheets.

60 My invention also consists in the unique shape of the bricks, arrangement upon the tubes, and location in the fire box whereby the objects named above, as well as other objects which will appear hereinafter, are 65 attained.

70 My invention will be more readily understood by reference to the accompanying drawings which illustrate preferred forms thereof, and in which—

75 Figure 1 is a central longitudinal section of a locomotive boiler fire box equipped with a fire arch embodying my invention; Fig. 2 is an enlarged detailed transverse section of the fire arch substantially on the line 2—2 of Fig. 1; Fig. 3 is a view similar to Fig. 2 but illustrating a modified form of my invention; Figs 4 and 5 illustrate different forms of the tube supported bricks; and Figs. 6, 7 and 8 illustrate various forms of 80 the inclined side or key bricks.

85 The form of my invention shown in the drawings is particularly designed for locomotive fire boxes in order to meet the peculiar conditions there prevailing. A locomotive arch in use is subjected to constant vibration and at times is severely shaken. This action frequently cracks or breaks certain of the bricks with the result that in 90 many of the arches hitherto devised the cracked bricks, and sometimes many other bricks of the arch fall into the fuel bed. The beneficial effect of the arch is thereby destroyed and the efficiency of the boiler 95 therefore diminished. In other instances, even when there are no broken bricks, the construction of the arch is such that the constant vibration of the locomotive, combined with severe jolts at times, causes one or more of the bricks to creep off the tubes 100 and fall into the fuel bed.

I shall now describe in detail my arch which cures the defects mentioned above and which also has many other advantageous features.

105 The locomotive fire box, as here shown, comprises the flue sheet 2, side sheets 3, 3, rear sheet 4, and crown sheet 5. Flues 7

extend forward from the upper part of the flue sheet and communicate with the smoke box at the front end of the locomotive. The fire box formed by the front, rear, and 5 crown sheets is inclosed by the outer or boiler shell 8 which is spaced therefrom to form the front, side, and rear water legs 9, 9' and 9''. Most locomotives are now 10 equipped with arch-supporting tubes and to such locomotives my invention can be applied without alteration, but with the fire boxes not containing arch tubes it is necessary to install a group of arch supporting tubes. The arch tubes 10 extend from the 15 lower part of the flue sheet 2 to the upper part of the rear sheet 4, thus occupying an inclined position. Water flows through these tubes from the front water leg 9 to the rear water leg 9'' and protects the tubes 20 from burning.

There are several types of locomotive fire boxes, which differ primarily in width, two of the well known types being the "wide" type and "narrow" type. In all types of 25 fire boxes, however, the arch tubes serve the same functions, the numbers therof being varied to accommodate bricks of convenient size and shape, which is usually determined by that size of brick which can be passed 30 through the fuel door. Arches are sometimes located on the arch tubes near the flue sheet in which instance they are termed "front" arches, and sometimes near the rear sheet in which instance they are termed 35 "rear" arches. The tubes 10 are usually arranged equally distant between centers throughout the width of the firebox, and the outermost tubes 10', which I shall herein term the "side tubes", are spaced from the 40 side sheets, in this instance, slightly less than the distance between tube centers. On the arch tubes 10 near the flue sheet, I arrange refractory bricks forming an arch. This arch is therefore a "front" arch but I wish 45 it to be understood that my arch is adapted for installation either as a "rear" arch or as a "front" arch. The arch is composed of a plurality of substantially identical bricks 11, which rest on the arch tubes 10. The bricks 50 11 are preferably of a width equal to the distance between the centers of the arch tubes so that they normally rest at each end upon half of the adjacent arch tube and they are 55 preferably substantially rectangular in transverse section so that the abutting edges of the bricks will properly withstand considerable side thrust without danger of either brick climbing upon the other. The bricks 11 which rest upon the arch tubes are 60 substantially laterally co-extensive with the arch tubes, and they shall be referred to as the "arch body". The bricks 11 which have their sides resting upon the side tubes 10' shall be referred to as "side bricks". 65 To close the space between the "side bricks"

and the side sheets, I preferably provide upwardly inclined key bricks 12—12, which rest upon the "side bricks" of the arch body, and which wedgingly engage the side sheets. The weight of the key bricks 12 70 tends to move the bricks of the arch body upon the tubes. Hence the action of oppositely inclined key bricks is to compress or press tightly together the various bricks comprising a transverse row of the arch body. This action is augmented by the vibration of the locomotive, so that the individual bricks of the arch are bound into a rigid whole. Now, should either or any of the bricks of the "arch body" become 75 cracked or broken, the pressure of the other bricks against it, caused by the key bricks 12, tends to prevent it from falling into the fuel bed. If the brick should be so badly broken that it would fall from the tube notwithstanding the pressure of the key bricks, the key bricks would shove the other bricks off the tubes, unless means are provided to limit the transverse movement of the "arch body" bricks. Therefore I provide the 80 bricks 11 with stops 11' on their undersides which only permit limited movement. The stops 11' are preferably spaced from the sides of the brick a distance slightly greater than the radius of the arch tubes. This will 85 permit them to move slightly, but will not permit them to move enough to fall from the tube in an integral condition. The stops are 90 preferably of the lug or rib construction and arrangement, shown in Figs. 4 and 5, since the weight of the bricks is thereby kept at a minimum, but they may be formed by a 95 solid depending bottom portion.

Since the key bricks 12 are inclined upwardly and since the lower end rests upon the side bricks of the arch body, the tendency is for the lower end to slide inwardly on the arch body and downwardly on the side sheets of the firebox. To prevent this I 100 preferably provide the lower end with ribs or lugs 12' so that the key brick has a portion 105 abutting the top of the body brick and a portion abutting the side of the body brick as clearly shown in Fig. 2. The lugs 12' 110 may be arranged either as shown in Figs. 6, 7 and 8 or in any other suitable manner.

Another advantageous feature of my construction is that the brick is adapted to slight irregularities in the spacing of the arch tubes. When the arch tubes are built in a locomotive at the time of its construction, the arch tubes are generally parallel and equally spaced throughout the width of the fire box, but at times due to the arrangement and location 115 of the stay bolts and for other reasons, it is not possible to space them absolutely equally distant.

When the tubes are installed in old locomotives it is even more difficult to secure uniform spacing of the arch tubes. The result 120

is that several sizes of brick for a given size of fire bricks must be provided or else the bricks must be made adjustable in some manner to fit tubes which are arranged in different spaced relation. In many of the arches hitherto devised adjustability has been accomplished by providing the bricks with variously arranged inclined edges, but the objection to such bricks is that there is no positive means limiting the movement of the brick, and the result is that the bricks often work off the tubes when subjected to constant vibration. Further, when bricks of this construction are subjected to a side thrust, such as is caused by key bricks arranged between the side sheets and the sides of the arch body, the bricks tend to climb upon one another so that one end moves from its support and the brick falls into the fuel bed. The bricks of my arch will accommodate themselves to irregularities in tube spacing without danger of falling off the tubes from either of the causes above mentioned, because of the positive stop lugs on the bricks.

The modified form of my invention shown in Fig. 3 differs from that shown in Figs. 1 and 2, in that the arch supported bricks have raised upper portions 11" against which the key bricks 12" abut. With this form of arch I am enabled to dispense with the ribs or lugs 12' upon the underside of the key bricks 12 (see Figs. 6, 7 and 8).

The embodiment of my invention shown overcomes many of the defects which are prevalent in the locomotive fire arches now in use, and also many of the objections urged against the vast number of locomotive fire arches hitherto devised but not embodied in operative structures. I can, however, conceive of other modified forms of arches which could be constructed without departing from the spirit of my invention and I do not therefore wish to be confined or limited to only the embodiments of my invention herein shown and described.

Having described my invention what I claim as new and desire to secure by Letters Patent is.

1. A fire arch comprising supporting tubes; bricks, forming an arch body loosely resting upon said tubes and abutting each other; means on said bricks for permitting only limited transverse movement thereof transversely with respect to said tubes; and

inclined key-bricks resting upon the side bricks of the arch body and against the sides of the fire box, substantially as described.

2. A fire arch comprising supporting tubes, fire bricks having their ends loosely resting upon adjacent tubes and abutting the ends of adjacent bricks, stop lugs extending downwardly between said tubes, said lugs being positioned to permit slight movement of said bricks but not sufficient movement to permit them falling between said tubes, and inclined key-bricks resting upon the side bricks and against the sides of the firebox, substantially as described.

3. A fire arch comprising supporting tubes; fire bricks having their ends loosely resting on adjacent tubes and abutting the ends of adjacent bricks; stop lugs extending downwardly between said tubes, said lugs being positioned to permit slight movement of said bricks but not sufficient movement to permit the bricks falling between said tubes; and inclined key-bricks resting upon the upper outer corners of the end bricks and against the sides of the fire box, substantially as described.

4. In a locomotive boiler firebox, a group of longitudinally extending arch tubes of less width than the firebox, an "arch body" supported on said tubes and laterally co-extensive therewith, said "arch body" comprising a plurality of abutting brick, each one resting upon two adjacent tubes, and having stop portions depending between tubes and slightly spaced therefrom, inclined key bricks resting upon the "side bricks" of the arch body and against the side sheets and pressing the brick of the arch body together, as and for the purpose specified.

5. In a locomotive boiler fire box a group of longitudinally extending arch tubes of less width than the fire box and an arch body supported upon said tubes and comprising a plurality of abutting bricks, each of which rests upon two adjacent arch tubes and is provided with stop portions depending between the tubes and slightly spaced therefrom, as and for the purpose specified.

In testimony whereof I have signed my name to this specification in the presence of two subscribing witnesses.

CHARLES EUGENE MILLER.
